UNITED STATES PATENT OFFICE.

GEORGE HENRY WHEARY, OF RACINE, WISCONSIN, ASSIGNOR TO WHEARY TRUNK COMPANY, OF RACINE, WISCONSIN, A CORPORATION OF WISCONSIN.

BAGGAGE CARRIER.

Application filed April 11, 1925, Serial No. 22,333. Renewed March 28, 1927.

This invention relates to certain new and useful improvements in baggage carriers of that type illustrated in copending application filed Aug. 20, 1924 and bearing Serial 5 Number 733,099.

In this form of baggage carrier, the movable section, which has been illustrated as the drawer section, closes over an extension carried by the normally stationary or wardrobe section, the drawer section being supported when in open position by a leg structure which is adapted to collapse as the 10 drawer section moves over the extension. When the leg collapses to permit the closing 15 of the drawer section over the wardrobe section extension member there is a slight tendency on the part of the drawer section to sag if heavily packed and this invention has as one of its objects the provision of anti-friction means for supporting the drawer section after its supporting leg becomes 20 inoperative in order to facilitate the closing movement of the section and to relieve the hinges of undue strains.

Another object of this invention is to provide adjustable anti-friction means for releasably supporting the drawer section as it moves over the extended member of the 25 drawer section.

It is a further object of this invention to provide a wear-plate, preferably of metal, which is mounted at one end of the extended member and over which the collapsible leg moves as the drawer section is closed, the 30 plate being provided with an aperture or opening if necessary to accommodate any projections or extensions of the leg member when collapsed.

And a still further object of this invention 35 resides in the provision of a secret compartment or drawer which is concealed beneath the plate covering the extension member for supporting the anti-friction roller and over which the collapsible leg moves while collapsed.

With the above and other objects in view which will appear as the description proceeds, my invention resides in the novel construction, combination and arrangement of parts 40 substantially as hereinafter described and more particularly defined by the appended claims, it being understood that such changes in the precise embodiment of the herein disclosed invention may be made as come within 45 the scope of the claims.

In the accompanying drawing, I have illustrated one complete example of the physical embodiment of my invention constructed according to the best mode I have so far devised for the practical application of the 50 principles thereof, and in which:

Figure 1 is a fragmentary view, partly in section and partly in elevation, taken through the lower portion of a wardrobe trunk embodying my invention and illustrating the 55 drawer or movable section as in partially open position, and

Figure 2 is an enlarged fragmentary view, partly in section and partly in elevation, taken through Figure 1 on the plane of the 60 line 2—2, the drawer section being illustrated in fully closed position.

Referring now more particularly to the accompanying drawing, in which like numerals designate like parts throughout the 65 several views, the numeral 5 designates the wardrobe or normally stationary section and 6 the drawer or movable section of a wardrobe trunk. The wardrobe section includes side panels 7, but one being shown, a rear or 70 outer panel, not shown, and a bottom 8, and the drawer section includes side panels 9, an outer panel, not shown, and a bottom wall 10, the sections being hingedly connected by 75 a suitable hinge, not shown, connecting the marginal edges of the two adjacent side panels thereof. The sections have been but fragmentarily illustrated and are adapted to be releasably locked in closed position by 80 any desired type of mechanism, not shown.

As described in the Letters Patent above mentioned, the bottom of one of the sections is disposed on a higher plane than the bottom of the other and is adapted to close over an extension member 11 projecting from the 85 bottom of the other section. In this embodiment, the drawer section is the one having its bottom on the higher plane, although it will be readily understood that the extension member may be formed on either section.

The extension member may be formed on the section 5 by extending its bottom wall 8, as at 12, and building side and outer walls 13 thereon of a height sufficient to align with the bottom edges of the adjacent walls of the 90 drawer section when closed thereover. This construction forms a compartment or space 14 in the extension member which may be 95 utilized in any manner and which is preferably closed by a removable cover or closure 100 105 110

15, the inner end of which is hingedly supported, as at 16, from a partition member 17 connecting the side panels of the extension member at their point of union with the side panels of the wardrobe section.

The meeting edges of the walls or panels of the drawer section and the extension member are provided with suitable interlocking valance means 18 to insure a neat exterior 10 appearance and prevent the entrance of moisture when the sections are closed.

While the hinge fitting connecting the sections may be made sufficiently strong to support the weight of the drawer section, even 15 though heavily packed, it is desirable to provide means supporting the outer free end thereof to relieve the fitting of a portion of the weight and consequently prevent the placing of undue strains on the side panels of the 20 section. To this end I provide the supporting leg structure which may be of the type illustrated in copending application filed December 17, 1924, bearing Serial No. 756,466.

25 Briefly stated, the supporting leg illustrated includes a supporting leg proper 19 which is pivotally secured, as at 20, to a plate 21 fixed to the outer panel of the drawer section adjacent its inner, lower marginal edge. 30 The bottom wall 10 of the drawer section is preferably slotted or cut-away, as at 22, to permit the projection of the leg below the drawer section and the mechanism mounted above the bottom is preferably enclosed in a 35 housing 23 to prevent interference with its operation by garments or other articles being caught therein.

The outer free end of the leg 19 carries a roller or other floor engaging member 24 and 40 the upper or inner end of the leg is provided with a locking lug 25 which is engageable in a locking recess 26 in a latch member 27 pivotally mounted on the plate 21 and normally urged to engage its locking recess with 45 the locking lug. Formed on the inner end of the lug is an arcuate arm or extension 28 which, when the leg is in collapsed position illustrated in Figure 1, extends into the extension member below the plane of the upper 50 edge of the outer panel 13, so that opening movement of the drawer section will engage the arm 28 with the extension member upper panel and swing the leg to a vertical or active position when its locking lug will engage in 55 the locking recess to thus firmly secure the leg in active position. In the closing movements of the drawer section the latch member is actuated to free the leg by a trip element 29 of approximately V-shape, which 60 carries a projection 30 at its apex which is engageable with the outer free end of the latch element, one end of the trip element being pivoted to the arcuate lever and its other end normally in the plane of the leg 65 with a cam portion 31 adapted to engage the

outer panel 13 of the extension member as the drawer section closes to move the trip element on its pivot and cause the projection 30 to move the latch member free of the locking lug 25, thus permitting collapsing of the 70 supporting leg by the continued movement of the drawer section.

In order to accommodate the wear of the supporting leg when in collapsed position, the closure 15 terminates at a point spaced 75 from the adjacent end of the extension member and this space is closed by a plate member 31 which is preferably formed of metal and has an opening or slot 32 therein through which the arcuate arm 28 and the trip element 29 pass as the leg is collapsed. The plate 31 which may be removable, although it is preferably fixed in position, may form the top portion of a secret drawer or compartment 33 which is movable therein and 85 adapted to be secured in place by a suitable lock mechanism 34.

In order to prevent sagging of the drawer section in the event it is heavily packed as the supporting leg is collapsed, I provide an 90 anti-friction device in the form of a roller 35 on which the bottom 10 of the drawer section tracks in closing. The roller member 35 is suitably mounted in a carrying socket 36 which is carried by a supporting strap or bracket 37 adjustably secured to the interior side of the plate 31 by screw posts 38 and lock nuts 39, the roller 33 projecting above the plate 31 through an opening 40 therein. As will be readily obvious, the distance the 100 roller 33 projects above the plate 31 may be readily adjusted by the lock nuts 39.

From the foregoing description taken in connection with the accompanying drawing, it will be readily apparent to those skilled in the art to which an invention of this character appertains, that I provide an improved means for relieving the hinge structure connecting the sections of a trunk of the character described after the supporting leg for the drawer section has been collapsed to thus prevent difficulty in closing; that I provide means for preventing undue wear by the supporting leg when collapsed and that I provide means forming a secret compartment or 110 drawer.

What I claim as my invention is:

1. In a baggage carrier, a normally stationary member, a second member movable to and from a closed position over a portion of the 120 stationary member, a plurality of means for supporting the movable member out of frictional contact with the stationary member and the floor during its movement, and one of said means being thrown to an inactive 125 position upon and independent of the engagement of the movable member with the other of said means.

2. In a baggage carrier, a normally stationary member, a second member movable to and 130

from a closed position over a portion of the stationary member, a plurality of means for supporting the movable member out of frictional contact with the stationary member 5 and the floor during its movement, and one of said means being adjustable and adapted to support the movable member during its movement over the stationary member.

3. A baggage carrier, comprising a pair 10 of sections, a member extended laterally from one section and over which the other section is movable to a closed position, a plate positioned over a portion of the extended member, a roller carried by the plate for supporting the movable section during its movement over said extended portion, and a drawer movable under said plate and detachably secured thereto.

4. A baggage carrier, comprising a pair of 20 sections, a member extended laterally from one section and over which the other section is movable to a closed position, a compartment wall positioned within the extended member, and anti-friction means carried by 25 the compartment wall for supporting the movable member during its movement over the extended member.

5. A baggage carrier, comprising a pair 30 of sections, a member extended laterally from one section and over which the other section is movable to closed position, a substantially fixed plate extended partly over the extended member, access being had to the interior of the member from the top at one side of the 35 plate and a secret compartment concealed by said plate.

6. A baggage carrier, comprising a pair

of sections, a member extended laterally from one section and over which the other section is movable to closed position, a supporting leg 40 for the movable section when in open position, the supporting leg collapsing as the movable section closes over the extended member, and anti-friction means for supporting the movable member as it closes over the extended 45 member.

7. A baggage carrier, comprising a pair 50 of sections, a member extended laterally from one section and over which the other section is movable to closed position, a metal plate covering one end of the extended member, a supporting leg for the movable section when in open position, said supporting leg collapsing and moving over the metal plate as the movable section closes over the extended 55 member, a plurality of anti-friction means for supporting the movable member during its movement to and over said stationary member, and one of said anti-friction means constituting a part of said leg.

8. A baggage carrier, comprising a pair 60 of sections, a member extended laterally from one section and over which the other section is movable to closed position, a metal plate covering one end of the extended member, a supporting leg for the movable section when in open position, the supporting leg collapsing and moving over the metal plate as the movable section closes over the extended 65 member, and anti-friction means for supporting the movable member as it closes over the extended member.

In testimony whereof I affix my signature.

GEORGE HENRY WHEARY.
